AUTOGRAPHIC REGISTER AND METHOD

John T. Davidson and Bruce T. Bickel, Dayton,
Ohio, assignor to The Standard Register Com-
pany, Dayton, Ohio, a corporation of Ohio

Application January 2, 1942, Serial No. 425,904

15 Claims. (Cl. 282—16)

This invention pertains to recording apparatus, and more particularly to a strip separator and distributing apparatus and mode of operation, for optionally segregating one or more optionally selected copies of a manifolded record assembly for preservation in a special compartment.

For illustrative purpose, but with no intent to unduly limit the scope or application of the invention, it is here shown and described as embodied in a conventional type of autographic register.

It has long been common practice in autographic register operation to direct one of a superposed plurality of inscribed record strips into a special locked compartment to prevent tampering with the inscribed record thereon, while the inscribed portions of remaining strips of the plurality are divided into individual sheets for distribution. However, the construction of autographic registers has heretofore been such that it was possible to make only the lowermost strip of an assembly the "locked in copy." There are many instances in modern commercial practice wherein it becomes desirable to preserve intact and to protect some copy or copies other than the lowermost of the assembly. Such copy to be segregated may be the topmost or any one or more intermediate strips of the plurality.

The present invention provides means and a mode of operation by which any one or more strips of a superposed plurality thereof may be selected and diverted into a receiving compartment, without interference with the ejection from the register of other strips of the assembly.

Thus, the object of the invention is to provide an autographic register which will be simple in construction, and which may not only be economically manufactured, but will be more efficient in use, automatic in action, uniform in operation, having minimum parts, and unlikely to get out of repair.

A further object of the invention is to provide an autographic register with means for protecting any strip of the plurality comprising the manifolding assembly used therein from the inscription receiving position until it reaches the locked compartment.

A further object of the invention is to provide an autographic register with means for directing any copy of the plurality comprising the manifolding assembly used therein to a locked compartment without interfering with the issuance from the register of the remaining copies.

A further object of the invention is to adapt an autographic register wherein an enclosed chute directs any optionally selected one of the strips of the manifolding assembly into a locked compartment so that succeeding form lengths may be readily detached from the other strips below or above that which is so segregated.

A further object of the invention is to provide an autographic register having the advantageous structural features and inherent meritorious characteristics and mode of operation herein mentioned.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the drawings, wherein is shown the preferred but obviously not necessarily the only form of embodiment of the invention,

Fig. 1 is a perspective view of an autographic register embodying the present invention.

Fig. 2 is a longitudinal sectional view thereof taken on line 2—2 of Fig. 5.

Fig. 3 is an enlarged perspective view of a portion of the register illustrating the relation of the strip guide or chute with the conventional hold-down blade and register cover.

Fig. 4 is a fragmentary sectional view of the register showing the relation of the strip guide or chute with the hold-down blade and feeding means and the manner in which unenclosed strips are discharged from the register.

Fig. 5 is an end view of the register on line 5—5 of Fig. 2 showing the closure of the locked compartment and illustrating strip guide chute in section.

Like parts are indicated by similar characters of reference throughout the several views.

While for illustrative purpose, but with no intent to unduly limit or restrict the scope or application of the present invention, it has been shown in relation to an autographic register, it is to be understood that the strip guide or chute and the method of separating and handling superposed record strips may be applied to other recording machines.

In the drawings, 1 is an autographic register mounted upon a pedestal 2 containing strip supply and storage compartments 3 and 4 respectively. The superposed strips 5, 6 and 7 are withdrawn from the zigzag folded pack 8 within the supply compartment 3 and advanced over the writing table 9 by the feeding means 10, which for illustrative purposes is herein shown as comprising a positive pin type feed for use with marginally punched paper. However, it is to be understood that the present invention is not dependent upon the particular type of strip feeding device.

The writing table 9 is supported upon the pivotal members 11 for upward swinging motion about the pivots 12 located at the rear of the register. Also, carried by the pivotal members 60 11 are strip guides or rollers 12' for supporting

and guiding the strips 5, 6 and 7 as they are advanced from the stack 8.

Overlying the writing table 9 and enclosing the mechanism of the register is a cover plate 13 which is pivotally mounted on the front of the cabinet by the hinges 14. To enable the exposure of the superposed strips 5, 6 and 7 for the recording of the desired records thereon, an opening 15 is provided in the cover 13 in registry with the underlying superposed strips and writing 10 table.

Located immediately over the feeding means 10 and providing the front margin of the opening 15 is a duo-functional plate 16, which serves as a feed finger or hold-down plate for holding the superposed assembly or strips in engagement with the feeding means, and maintains the strips in aligned relation while relieving any strain on the strips and feeding means. The plate 16 is supported on the arms 17 for swinging motion about the pivot 18 and is normally maintained in spring tensioned relation with the strip assembly and feeding means by the spring 19.

Located immediately adjacent the forward edge of the plate 16 are interconnected relatively spaced members 20 and 21 which together form the completely enclosed guide or chute 22 for directing the desired strip to the locked storage compartment 4. The guide 22 being of arcuate shape, it initially extends in an upwardly direction away from the plate 16 and the cover 13, thereby providing ample room intermediate the guide and cover for the operator to manually grasp and detach from the lowermost superposed strips the succeeding forms thereof as they are issued from the register (Fig. 3).

The discharge end of the guide 22 is supported on the register 1 in aligned relation with the opening 23 to the storage compartment 4 by the hinges 24. The hinges 24 enables the guide 22 to be swung forwardly and downwardly away from the feeding means 10 and hold-down plate 16 to facilitate the opening of the register when it becomes necessary to thread a new supply of strips therethrough.

Located on the under side of the guide 22 is a tail piece or stop member 25, which as the guide swings upon its hinge connection limits the downward movement of the guide 22, by engagement with the stationary guide plate 26 located immediately inside the opening 23.

A modified usage of the present apparatus is also shown in Fig. 4, wherein the intermediate strip 6 is directed through the guide 22, the top-most strip 5, shown by dotted line, and the bottom strip 7 being issued above and below the guide 22 respectively.

There is thus provided a device for selectively dividing from the assembly of superposed strips a preselected strip or strips from the plurality thereof and directing such preselected strip or strips to the locked storage compartment without interfering with the discharge from the register of over or underlying strips of the assembly.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more

or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described our invention, we claim:

1. An autographic register, wherein an assembly of superposed strips of record material is progressively advanced past a recording position from the register, characterized by a cabinet having a discharge opening for said strips, a normally locked storage compartment to receive at least one of the strips, a protective guide chute, wherein an advancing strip is inaccessible, leading from the discharge opening of the cabinet to the storage compartment through which the top, bottom or intermediate portion of the strip assembly is selectively discharged into the storage compartment to the exclusion of the remainder of the strip assembly, and optionally selective discharge passages to the exterior of the register above and below the entrance to the guide chute through either or both of which remaining strips of the assembly other than the strip or strips being directed through the chute may be discharged from the register.

2. An autographic register, wherein an assembly of superposed strips of record material is progressively advanced past a recording position, a normally inaccessible storage compartment, a plurality of guide passages, one of which discharges into the said storage compartment, and through which one or more intermediate strips of the assembly are directed into said compartment and the remainder of which discharge outside the register, and through which top and bottom strips of the assembly may be discharged beyond the register simultaneously with the discharge of intermediate strips into the storage compartment.

3. An autographic register, wherein an assembly of superposed record strips are progressively advanced past a recording position the top and bottom portions thereof being discharged from the register and the intermediate portion deposited in a storage compartment, including dual discharge passages for the top and bottom portions of the strip assembly leading to the exterior of the register, and an intermediate guide chute extending to the storage compartment through which the intermediate portion of the assembly is advanced into the compartment.

4. The herein described method, including advancing an assembly of superposed record strips in unison past a recording position and thence past a point of separation, detaching from a portion of the assembly including the uppermost and lowermost strips thereof successive terminal portions, and directing the intermediate strips of the assembly to a storage compartment in strip form.

5. The herein described method, including the steps of advancing a plurality of superposed record strips in unison past a recording position and thereafter separating the strips and diverting an intermediate portion thereof into a normally inaccessible receiving compartment simultaneously delivering the remainder of the strip assembly into an accessible position.

6. An autographic register, wherein a plurality

of superposed record strips are advanced in unison past a recording position, and subsequently separated, including a storage compartment, plural guide passages appropriately directing top, bottom and intermediate strips of the assembly, one of which delivers selected strips into the compartment, and the others of which deliver other strips of the assembly outside the compartment, the construction and arrangement being such that either the top, the bottom, or the intermediate strips of the assembly may be optionally delivered into the compartment simultaneously with the delivery of the remaining strips outside the compartment.

7. An autographic register, wherein an assembly of superposed strips are advanced from a supply thereof past a record receiving position and a portion thereof are advanced to a normally locked storage compartment and another portion thereof delivered outside the register, feeding means for advancing the strip assembly, a plurality of separate guide passages for separated portions of the assembly, including a protective guide chute means enclosing and directing an intermediate portion of the strip assembly to the storage compartment, the construction and arrangement being such that the unenclosed portions of the strip assembly may be issued from the register simultaneously with the deposit of the intermediate portion of the strip assembly in the locked compartment.

8. An autographic register, wherein an assembly of superposed record strips are advanced past a record receiving position, feeding means for advancing the assembly and means adjacent the feeding means for dividing from the assembly a preselected intermediate portion thereof, and separate guide passages for the selected intermediate portion of the strip assembly and the remaining portions thereof by which the divided portions are delivered to separate points.

9. An autographic register, wherein a portion of an assembly of superposed record strips, exclusive of the lowermost strip, is directed to a storage compartment, a hinged arcuate guide member normally maintained in operative position for enclosing and directing said portion of the assembly to the storage compartment, and stop means on said guide member defining the extreme limit of motion when in inoperative position.

10. In a recording apparatus, wherein a plurality of superposed strips of record material are simultaneously advanced past a recording position, strip feeding means, a hinged arcuate chute overlying the apparatus and extending into the path of advancement of the strips through which a segregated portion of the strips is advanced, an exit passage adjacent to the entrance to the chute through which another strip of the plurality is advanced preparatory to separation into individual sheets for distribution, and a receiver into which the chute discharges for reception of the segregated strip or strips.

11. In a recording apparatus, wherein a plurality of superposed strips of record material are simultaneously advanced past a recording position, strip feeding means, a chute overhanging the apparatus and extending into the path of advancement of the strips through which a segregated portion of the strips is advanced, exit passages above and below the chute through

which strips other than those directed through the chute are ejected preparatory to division thereof into individual sheets for distribution, and a receiver into which the segregated portion is discharged from the chute.

5 12. A strip separating apparatus, wherein an assembly of superposed strips are advanced in unison from a source of supply and separated into normally accessible and inaccessible portions, including strip feeding means for collectively advancing the strips, and a series of three guide passages through which the strips may be optionally directed, a protective chute defining the intermediate passage wherein one or more passing strips will be inaccessible and communicating with a normally inaccessible depository therefor, the outer passages of the series being operative to direct strips to an accessible point, the construction and arrangement being such that one or

10 15 more topmost, bottommost or intermediate strips of the assembly may be selectively directed through the protective chute into an inaccessible depository and the remaining strips simultaneously directed through either or both the remaining passages for immediate access thereto.

20 15 12. An autographic register, wherein an assembly of superposed record strips are collectively advanced past a record receiving position, including a plurality of optionally selective guide pas- 30 30 sages through either of which one or more strips of the assembly thereof may be directed, a protective chute defining one of the guide passages wherein passing strips will be inaccessible, an inaccessible depository for strips with which the

35 35 protective chute communicates, the remaining strips being directed to an easily accessible point, the disposition and arrangement of passageways being such that an undetermined optionally selected portion of the strips of the assembly may be directed through the protective chute into the inaccessible depository and other strips above or below those mentioned may be directed to an accessible point outside the said inaccessible depository.

40 45 14. A strip separating apparatus, wherein an assembly of superposed strips are collectively advanced from a source of supply and subsequently separated into accessible and inaccessible portions, including dual optionally selective guide

50 55 50 55 passages through either or both of which a portion or portions of the strips may be directed to an accessible point, and a protective guide chute wherein a passing strip is inaccessible communicating with a normally inaccessible depository through which topmost, bottommost, or intermediate strips of the assembly may be directed at will into said depository.

55 60 15. An autographic register, wherein an assembly of superposed record strips are collectively advanced from a source of supply past a record receiving position and subsequently separated into accessible and inaccessible portions, including an inaccessible depository into which a selected portion of the strips is directed and dual

65 70 65 70 passages through either or both of which the remaining strips may be directed to an accessible point, the construction and arrangement being such that the topmost, bottommost or intermediate strips may be optionally directed into the inaccessible depository.
